UNITED STATES PATENT OFFICE.

RAY M. McCLEARY AND GEORGE L. HARNLY, OF PHILADELPHIA, PENNSYLVANIA,
ASSIGNORS TO OSCAR L. SMITH, OF GRAND RAPIDS, MICHIGAN.

DISPLAY-RACK.

1,081,685.

Specification of Letters Patent. Patented Dec. 16, 1913.

Application filed September 2, 1910. Serial No. 580,152.

To all whom it may concern:

Be it known that we, RAY M. McCLEARY and GEORGE L. HARNLY, citizens of the United States, residing in Philadelphia, in 5 the county of Philadelphia and State of Pennsylvania, have invented certain new and useful Improvements in Display-Racks, of which the following is a specification.

This invention relates to improvements in 10 display racks for garments and other goods.

The principal object of the present invention is to provide a neat, simple, durable, efficient and comparatively inexpensive device wherein either the front or rear row of 15 garments supported on the device are rendered readily accessible for the purpose of exhibiting or removing the same.

A further object of the present invention is to provide a device of this character 20 wherein the entire device or rack is mounted or supported between bearings, so as to be shiftable back and forth, and wherein the rack portion of the device is rotatably mounted or supported.

25 A still further object of the present invention is to provide a device of the character indicated of neat and attractive appearance, which may be either directly or indirectly, as by a base or stand, be fitted to 30 a floor, window-bottom or other suitable place for exhibiting purposes, thereby eliminating the expense of a case or compartment.

Other objects of the invention relate to 35 the providing of general details of construction and arrangement of parts as will hereinafter appear.

With these and other objects in view, the invention consists of the improvements here- 40 inafter described and finally claimed.

The nature, characteristic features and scope of the invention will be more fully understood from the following description taken in connection with the accompanying 45 drawings forming part hereof and in which:

Figure 1, is a top or plan view partly in section of a display rack embodying the invention, Fig. 2, is a sectional view taken on the line 2-2 of Fig. 1, Fig. 3, is a sectional view taken on the line 3-3 of Fig. 2, and Fig. 4, is a view in section taken on the line 4-4 of Fig. 3.

Referring to the drawings, the display rack as a whole is mounted upon any suitable support, which as shown in the draw-

ings is a base 1, although obviously instead of the base, the display rack could be supported directly by a flooring or window-bottom if desired. Upon the base 1, or other support utilized, is mounted a hood or casing 2, flanged as at 3, in order that the same may be securely fastened as by screws or the like 4. Rotatably mounted within the hood or casing 2, which may be of cast metal or the like are flanged rollers 5, and 6. As 60 clearly shown in the drawings, particularly Fig. 2, these rollers 5, and 6, are mounted in different planes and are arranged one in advance of the other.

While the preferred form of bearing has 70 just been described, clearly other bearings as ball-bearings may be substituted without departing from the spirit of the invention.

Arranged for back and forth shiftable movement with respect to the hood or casing 2, is a rack supporting member 7, adapted to have its upper surface track upon the roller 6, and to have its lower surface track upon the roller 5. As clearly shown in Fig. 4, the member 7, is of rectangular cross-section and may have its center hollow as at 8, to lighten construction and further may have its four sides gouged as at 9, in order to save expense in surface finishing said member. The top and bottom surfaces of 80 the member 7, are recessed as at 10, and 11, and are provided with pins or stops 12, and 13, for a purpose presently to appear. The forward or exposed end of the member 7, may be circular, considered in plan, and is recessed as at 14, to receive a vertically disposed tubular section 15. The upper portion of the member 7, adjacent the recessed portion 14, thereof, terminates in an upwardly extending hub 16, which is longitudinally bored to register with an aperture 17, in the tubular section 15. A spring controlled shiftable bolt 18, is fitted to work through said bored and apertured portions for a purpose to be presently described. 90 Mounted for rotatable movement within the tubular section 15, is a rack supporting bar 19, the lower portion of which is provided with a shoulder 20, and a depending stem 21, passing through an aperture 22, in the base of the member 7. Between the bottom of the recessed portion 14 of the arm 7, and the shoulder 20 of the bar 19, is a thrust bearing 23. Adjacent the shoulder 20, the bar 19, is notched as at 24, and 25, which 100 105 110

notches are oppositely disposed whereby the above described bolt 18, engage one or the other of said notches when the bar 19, is in proper position for display purposes. A cap 26, surrounds the tubular section 15, to provide a bearing and a good appearance and to prevent dust and dirt from accumulating within said tubular section. Shown as being carried by the top of the bar 19, is a collar 27, equipped with arms 28, which act as a support for rods 29, for receiving and holding the garments to be displayed. A tapered pin 30, may be present for securing the collar 27, to the bar 19, to prevent slippage, it being understood that the collar 27, is forced over the bar 19, and that the tubular section 15, is forced within the recessed portion 14, of the member 7. Shown as fitted to the lower portion of the stem 21, of the bar 19, is a shoe 31, adapted for normally engaging an inverted T-shaped guide 32, which is supported by the base 1, as shown in Figs. 2, and 3. The shoe 31, is shown as being recessed to receive the stem 21, and the parts may be secured together by a tapered pin 33.

A brief description will now be given of the mode of operation of the above described display rack.

30 When it is desired to shift the display rack from the position shown in the drawings to another position, the member 7, is moved in the direction of the arrow in Fig. 2, until the roller 6, seats itself in the recess 35 10, upon the upper surface of the member 7, the stop 12, preventing further movement. By this movement of the member 7, the shoe 31, has cleared the track 32. The bar 19, including its arms 28, is then rotated to the 40 desired position. In this connection, it may be remarked that the bolt 18, may be readily disengaged from the notch 24, and when the notch 25, and bolt 18, register, notice is given to the operator, that the desired position has been obtained. The member 7, is 45 then pushed back until the roller 25, engages the notch 11, upon the under side of the member 7, at which time the shoe 31, has reengaged the track 32, and locked the 50 parts together.

From the construction described as one convenient and practical form of the invention, it will be noted that the rack for supporting the goods to be displayed is mounted on and movable with a supporting member or carriage which may be moved to and from an inner position with respect to the base on or over which it travels, and that when in its outer position the rack may be 55 rotated to display the goods at either side of the rack. It will also be apparent that the spring plunger 18 mounted on the carriage coacts with either of the notches 24 or 25 on the rack supporting member, so 60 that when the rack is properly positioned

for movement with the carriage 7, the spring plunger on the carriage will indicate the fact by obstructing the free rotative movement of the rack, and that when in such position and the carriage or rack is 70 moved toward inner position with respect to the base, or a case in which the rack may be associated, the rack will be prevented from rotative movement by the engagement of the members 31 and 32, which for convenience are designated the shoe and guide 75 respectively. It will thus appear that the plunger 18 on the carriage and the coacting recesses 24 and 25 of the rack act as an indicating means to indicate to the attendant 80 as he revolves the rack when it is in a position that he may safely push the rack backward with respect to the base or case. When the rack is pulled outward from the base or case and has reached its outer position, it 85 will be understood that the members 31 and 32 become disengaged, and at such time the rack may be rotated by exerting sufficient force to cause the pin or plunger 18 to rise out of or disengage either of the notches 24 90 or 25 with which it may be for the time engaged. It will also be noted that by reason of the fact that the pin or plunger 18 and the notches 24 and 25 are carried respectively one by the rack and one by the carriage, they move with the rack and carriage as the said rack and carriage are moved to and from an inner position with respect to the base or case, and that even should the shoe 31 and guide 32 be omitted, the pin 18 100 and notches 24 and 25 will still act to restrain free rotative movement of the rack as it is moved to and from its inner position.

What I claim is:

1. In a display device, the combination of 105 a case or cabinet, a carriage mounted in the case or cabinet for movement to and from an inner position, a tubular section 15 mounted on and movable with the carriage, a rack supporting bar 19 carrying a rotatable rack 29 and extending through said tubular section 15, a spring actuated pin 18 mounted in and movable with the carriage and extending through the tubular section 15 to the interior thereof, said rack supporting bar 19 being provided with notches 25 inside the tubular section 15 adapted to be engaged by said pin to prevent rotation of the rack as it is moved to and from its inner position and permitting it to be rotated 110 120 when in outer position.

2. In a display device, the combination of a case or cabinet, a carriage mounted for movement to and from a position within said case or cabinet and having a hub portion 125 16 provided with a longitudinal bore, a tubular section 15 mounted within said hub and provided with an opening registering with the longitudinal bore of the hub, a rack supporting bar within said tubular section and 130

carrying a rotatable rack, said bar being provided with notches, and a spring actuated pin mounted in the longitudinal bore of the hub and extending through the opening in the tubular section to engage the notches in the rack supporting bar.

3. In a display device, the combination of a case or cabinet, a carriage movable to and from a position within said case or cabinet, a rotatable rack carried by the carriage and movable therewith to and from a position within the case or cabinet, and a spring actuated pin and coöoperating notches, one rotatable with the rack and the other on the carriage to restrain free rotative movement of the rack as it is moved to and from a position within the case or cabinet.

4. In a display device, the combination of a base, a hood 2 secured to the base and having a longitudinal recess, a rack support 9 extending longitudinally within said hood, and having a hub-like forward end 16, roller guiding means 5 and 6 within said hood and disposed at opposite sides of the rack support, a rotatable rack mounted in said hub-like forward end of the rack support,

and means mounted in the wall of said hub-like portion and engaging a part connected to the rotatable rack to restrain free rotative movement thereof.

5. In a display device, the combination of a base, a hood secured to the base and having a longitudinal recess, a rack support extending longitudinally within said hood, and having a hub-like forward end, said rack support also having recesses to limit its forward and rearward travel, roller guiding means within said hood to engage said recesses, a rotatable rack mounted in said hub-like forward end of the rack support, and means mounted in the wall of said hub-like portion and engaging a part connected to the rotatable rack to restrain free rotative movement thereof.

In testimony whereof, we have hereunto signed our names.

RAY M. McCLEARY.
GEORGE L. HARNLY.
